(57) CLAIM

The ornamental design for a lamb bone shaped dog treat, as shown and described.

DESCRIPTION

FIG. 1 is a top plan view of a lamb bone shaped dog treat showing my new design, the bottom plan view being a mirror image; and,

FIG. 2 is a side perspective view of FIG. 1, the opposite side being substantially the same, the only differences being the dimensions and contours of the simulated meat and fat, which follow the dimensions and contours thereof shown in FIG. 1.
